AUTOMOBILE HEADLIGHT PROTECTOR

William J. Flajole, Detroit, Mich.

Application July 19, 1950, Serial No. 11,259

Term of patent 7 years

(Cl. D48—32)

To all whom it may concern:

Be it known that William J. Flajole, a citizen of the United States of America, and a resident of Detroit, in the county of Wayne and State of Michigan, has invented a new, original, and ornamental Design for Automobile Headlight Protector, of which the following is a specification, reference being had to the accompanying drawing, forming a part thereof and wherein:

Fig. 1 is a perspective view of an automobile headlight protector, showing my new design;

Fig. 2 is a front elevational view thereof; and

Fig. 3 is a sectional view taken along the line 3—3 of Fig. 2.

The dominant features of my design are shown in solid lines in the drawing.

I claim:

The ornamental design for an automobile headlight protector, substantially as shown and described.

WILLIAM J. FLAJOLE.
